ELECTRONIC DISTRIBUTOR FOR MULTIPLEX PULSE COMMUNICATION SYSTEMS

Max H. Mesner, Princeton, N. J., assignor to Radio Corporation of America, a corporation of Delaware

Application September 24, 1946, Serial No. 698,931

17 Claims. (Cl. 179—15)

1

This invention relates to electronic distributors and more particularly to a device for use in multiplex communications systems. My invention makes it possible to multiplex any desired kind of signals without appreciable distortion by compressing each signal train into discrete channel-time units, transmitting the compressed signal components for the different channels in successive order, and expanding the same after reception so as to restore their original frequency characteristics and continuity.

The instant application is a continuation in part of my co-pending application Serial No. 496,921, entitled "Multiplex system," and filed July 31, 1943, now abandoned.

In multiplex systems, the present trend of design is to do away with all moving parts such as rotary commutators, magnetic selecting relays, and the like. It is advantageous to perform the necessary switching functions for impressing signals successively on different channels by means of electronic switches. One known method is to arrange a series of electron discharge tubes with circuit parameters such that each tube is activated in succession and prepares a succeeding tube for activation. If, therefore, the multiplex system requires transmission of separate trains of signals on three different multiplex channels, then three such discharge tubes in the electronic distributor would be provided and transmission on each channel would take place during the period of activation of each individual tube.

Another known method of electronic switching requires the use of a special cathode ray tube having a plurality of target anodes against which an electronic stream is directed from a gun in the tube. The deflecting means operates cyclically and the electron beam is controlled by means of the signals. It, therefore, follows that different signals may be directed into different channels each associated with one of the target anodes.

My improvements in electronic switching are entirely different from those described in the foregoing paragraphs.

Cathode ray tube technique is preferably employed in such a manner that by one scanning operation intelligence is stored in the form of electronic charges spread over a field. The scanning operation herein referred to is intended to mean that electrons emitted by a so-called "electron gun" are deflected toward different portions of a field or target. Such a target as employed in my invention is composed of an array of mutually insulated linear conductors arranged

2

preferably as elements of a cylindrical surface and backed by a conducting plate which is spaced from the conductors by a dielectric of substantially uniform thickness. The intelligence to be transmitted is broken up into different portions, each portion of which represents a scanning cycle. The storing operation of the transmitter is, however, continuous. During the latter portion of each scanning cycle of a so-called "put-on" beam, a second scanning operation takes place by means of a second or "take-off" beam which removes the stored intelligence at an accelerated rate, transferring it to an amplifier.

Accordingly, a method will be explained and apparatus described in the instant disclosure for performing this method wherein an individual signal is impressed on the control grid of an electron gun constituting one unit in a specially constructed cathode ray tube where two such guns are provided. Independent deflecting means are associated with each gun. The beams, however, are directed against the aforementioned target which serves as an anodal screen and possesses a function similar to that of the well-known cathode ray tube screens used in television apparatus of the iconoscope type. The tube is also provided with a second gun having separate deflecting means associated therewith. The scanning rate for the two beams is made quite different, although the repetition rate is the same. The two beams will be hereinafter referred to as the "put-on" beam and the "take-off" beam respectively. If the scanning velocity of the "take-off" beam is made three times as great as that of the "put-on" beam, then a three-channel multiplex system is provided. Two thirds of the cycle is used as a rest period for the beam which is deflected at the greater scanning velocity. As a result, the intelligence taken from the tube is condensed as to time and is transmitted in only a fraction of the distributor cycle. This leaves rest periods during each cycle in which other similarly condensed signals may be transmitted. Such a two-gun cathode ray tube may be called a commutator tube and would be provided for each channel in the multiplex system.

It is an object of my invention to provide an electronic distributor for multiplex systems. It is another object of my invention to provide a multiplex system in which time division is obtained as between different channels and wherein the total signal for each channel is condensed so

as to be entirely included in the channel time allotted thereto.

It is still another object of my invention to provide electronic distributor apparatus whereby signals are condensed as to time in order that different signal trains may be transmitted successively and, upon reception, may be distributed to different responsive devices, and translated by expansion back into their original form.

Other objects of my invention, as well as certain advantages thereof, will best be appreciated as the details of the disclosure are brought out. The following description is accompanied by drawings, in which:

Figs. 1 and 1a (when joined together) show diagrammatically a preferred transmitting circuit arrangement including electronic distributors for three separate channels in a multiplex system;

Fig. 2 shows a suitable scanning circuit for the "take-off" beam of a cathode ray tube distributor;

Fig. 3 shows a corresponding scanning circuit for the "put-on" beam;

Fig. 4 shows a block diagram of receiving apparatus which is associated with electronic distributors of the type herein disclosed; and

Figs. 5 and 5a (when joined together) show certain details of a circuit arrangement for association with the cathode ray receiving distributor which I preferably employ.

At the outset it should be understood that I do not claim as my invention any of the improvements to be found in the special cathode ray tube having two guns and a screen-like target composed of parallel conductors which are insulated one from another. The details of such a construction are fully disclosed in a copending application of Harley Iams et al., Serial No. 492,658, filed June 26, 1943.

The two-gun cathode ray tube

In order to more understandably follow the ensuing description of my improved circuit arrangements, the essential details of construction of the aforementioned special cathode ray tube having two guns will first be set forth.

Although the same tube may be used both for transmission and for reception, the essential details of the tube structure are best shown in Fig. 5, in association with a receiving circuit. The tube comprises a high evacuated envelope having a bulb portion 10, in which a storage screen is mounted. This screen is a target anode having parallel-disposed conductors 24 which are insulated one from another.

The "put-on" gun is mounted in the neck portion 12 and the "take-off" gun is mounted in the neck portion 13. The "put-on" gun emits one beam of electrons, and the "take-off" gun emits a second beam. High electron velocity and low electron velocity beams (as distinguished from scanning velocities) are sometimes used for the "put-on" and "take-off" operations respectively, and in much the same manner as has been found successful in television technique, as is well known.

One gun has a cathode 16, a control grid 17, a first anode 18, and a second anode 20, if desired. A collector electrode 21 is provided to collect secondary electrons from the storage screen 11. Lateral deflection of the "put-on" beam may be produced by means of a pair of deflecting plates 22. Other deflecting plates 25 may be provided for beam focusing as is explained in the aforementioned copending application of Iams et al. Operating voltages that may be applied to

the various tube electrodes are indicated on the drawing merely by way of example. These operating voltages may, if desired, be derived from different taps on a potentiometer 8 which is connected between the positive and negative terminals of a direct current power supply source. An intermediate point on this potentiometer is grounded. Ground potential is also applied to the anode 21 and to one of the deflecting plates 22.

The storage screen 11 may be constructed in various ways. In one of the preferred constructions, as indicated in the copending Iams et al. application, it comprises a supporting sheet of mica about 0.001 inch thick which has an array of parallel conducting strips or lines 24 extending horizontally across the screen. These strips may be formed, for example, by sputtering a conductive coating of platinum upon each side of the mica sheet and then using a ruling machine to scratch about 100 lines to the inch on the front so as to separate the metal into conducting lines. The metal coating on the back side of the mica sheet may be used as the signal plate for taking off the signal, if desired.

In order to insure the operation of the "put-on" gun so that the ratio of secondary electrons to primary electrons shall be greater than unity, a small amount of caesium may be inserted in the tube during its manufacture. It is preferred, however, that the screen 11 shall not be photoelectric in action. Therefore, no oxidizing step is required preliminary to the introduction of the caesium.

The screen 11 when mounted in the tube preferably is curved to conform to the surface of a cylinder having an axis that passes through or near the centers of deflection of the two electron beams, whereby the point of smallest beam diameter is always at the screen surface as the beam is deflected and whereby the beams during deflection are substantially at right angles to the screen surface where the beam strikes. This feature is particularly important in the operation of the low velocity beam.

In operation the incoming signal is applied to the control electrode 17 to modulate the intensity of the high velocity beam as it is deflected transversely across the conducting strips 24. The number of secondary electrons liberated from the strips exceeds the number of beam electrons, and since substantially all of the secondary electrons are drawn over to the collector electrode, they are not redistributed over the target 11. Hence, the bombarded strips 24 are given a more positive potential.

At the other end of the screen 11 the conducting strips are scanned at a greater speed by deflecting the low velocity electron beam transversely by means of a deflecting coil 30. If the electrons of this beam strike the conducting strips 24 with a relatively low velocity, the ratio of secondary electrons to primary or beam electrons (those of the beam) is less than unity. Accordingly, sufficient beam current is provided to return the conducting lines to the potential of the cathode supplying this low velocity electron beam. Thus the signal "put-on" by the first beam is substantially completely wiped off by a single scanning of the second beam.

The output signals produced by this "wiping-off" action may be derived from a signal plate SP on the back side of the screen 11, or they may be derived from a collector electrode 200, or from an electron multiplier receiving the unused elec-

trons from the "take-off" beam as they return from the screen 11. These methods of taking off a signal from a storage screen are well known in connection with the operation of Iconoscopes and Orthicons. The electron multiplier arrangement for receiving the unused electrons from the "take-off" beam is illustrated and described in connection with Fig. 1 of copending application Serial No. 492,658, now Patent No. 2,454,652, granted November 23, 1948, filed by Iams et al., to which reference is made.

If either of the above described methods of taking off the signal is employed, the tube is provided with a mica partition 201 to prevent secondary electrons emanating from the upper portion of screen 11, produced by the "put-on" beam from reaching the electron multiplier or collector electrode located in the lower neck 13 of the tube. Also, a metal ring electrode 202 near the partition may be provided and held at a negative potential to repel any secondary electrons that might otherwise get past the mica partition.

In the example illustrated, the "take-off" beam is produced by an electron gun which comprises a cathode 36, a control electrode 37, a screen grid 38, a first anode 39, and a second anode 41. One or more electrodes such as 42 are positioned between the second anode and the screen 11 for slowing down the electrons after they leave the region of the second anode.

The transmitter

A block diagram of a preferred circuit arrangement for the transmitting station is shown in Figs. 1 and 1a. In order to maintain a suitable phase difference between the operation of the different cathode ray tubes 10a, 10b, and 10c respectively, a single oscillation generator 1 producing sine waves is provided in combination with a delay network comprising series capacitors 2 to 6 inclusive and shunt resistors R2, R3, R4, R5, and R6 respectively. This network has its components so chosen that a phase difference of 60° between the different taps from the network is obtained. The energy from the generator 1 is, therefore, fed directly, and with zero phase, to a limiter and pulse generator circuit 12. With a 60° delay, it is also fed to a limiter and pulse generator 14. The details of these limiters 12 and 14 will be hereinafter described in more detail. The output from the pulse generator in the unit 12 is used to control a saw-tooth generator 15. This generator delivers an output which has its peaks clipped by the device 18. The output from the unit 18 is then amplified in a device 20 and fed to a deflection coil or coils 30a associated with the "take-off" gun in the cathode ray tube 10a. The circuit is completed to ground through a centering potentiometer 31. The tap on potentiometer 31 is coupled to ground across a capacitor 32a.

The limiter and pulse generator unit 14 operating with a 60° phase lag compared with potentials fed to the limiter 12 is used to control a saw-tooth generator 23 which delivers its output to an amplifier 26. The amplified energy is fed to one of the deflecting plates 22 in the "put-on" gun of the cathode ray tube 10a. The opposing beam deflecting plate 22 is connected to ground. As a matter of fact, the 60° delay relationship in the output from the amplifier 26 compared with that from the amplifier 20 should be considered in a different sense; that is to say, the beam deflection produced by the electrostatic plates 22 has a 300°

lead over that of the deflecting action of the coils 30a. In other words, a signal which is "put-on" by the beam emanating from the cathode 16 precedes the "take-off" action produced by the beam emanating from the cathode 36.

The intelligence or signal impressed upon channel A may comprise suitable source of modulation. It is herein shown as originating at a microphone 40. The intelligence may, however, be other types of signals, such as television and facsimile, rather than speech as shown. The signal is amplified by the unit 43 and applied to the control electrode 17 through capacitor 44, by producing potential variations across the input circuit resistor 45. This resistor terminates in a tap 46 on a voltage divider, the different sections of which extend across the terminals of a direct current potential source.

As will be understood from the foregoing description of operation of the cathode ray tube, the incoming signal is impressed upon element 17 as a result of which, in conjunction with the scanning, there will be a series of charge patterns continually impressed upon the target screen 11a, the linear elements 24 of which are arranged to be scanned by the operation of the beam deflecting potentials impressed on the electrostatic plates 22. As has also been explained, the "take-off" operation is intermittent because the scanning produced by the deflecting coils 30a operates under control of a clipped saw-tooth wave derived from the amplifier 20. The scanning velocity of the "take-off" beam is three times as great as that produced by the electrostatic plates 22 which affects the "put-on" beam. The "take-off" gun is here considered as operating in zero phase relation to the source 1. By selection of suitable values for the time constant elements 65 and 69 and by the use of the clipper diode unit 18 (note Fig. 2) the actual scanning time of the "take-off" beam is reduced to one-third of the scanning time of the "put-on" beam. This permits rest periods to take place in the output from the screen 11a sufficient for the impress on the transmitter modulator of signals pertaining to channels B and C.

The circuit arrangements for channels B and C are identical with channel A and need not, therefore, be described in detail. It should, however, be noted that the different sections of the delay network comprising the shunt capacitors 3 to 6 inclusive and series resistors R3 to R6 inclusive provide the necessary delay action in the scanning potential circuits so that the total transmission time for the multiplex system may be engaged by the "take-off" beams of the three cathode ray tubes 10a, 10b, and 10c in succession.

From one only of the beam deflecting circuits of the "take-off" guns, that is to say, from the circuit which feeds through the deflecting coils 30a, synchronizing potentials are derived for transmission over the radio channel. In series with coil 30a is a resistor 31a from which the required synchronizing pulses are derived. These pulses are used in a differentiator circuit and then amplified in a pentode tube 34. The differentiating action is obtained by means of capacitor 32 and resistor 35 the values of which are suitably chosen for the purpose. The maximum potential drop through resistor 31a occurs at the instant of the return stroke of the saw-tooth scanning cycle. The input circuit for tube 34 includes grid resistor 35 which is connected to ground. Capacitor 26 couples the cathode of tube 34 to ground and is in shunt with the cathode resistor R8.

The signal potentials which arise from the sequential scannings of the "take-off" beams in the three cathode ray tubes are drawn through separate diodes 48a, 48b and 48c in order to kill the noise effects of the positive charges on the target screens 11a, 11b and 11c which may result from the scannings of the screens by the "put-on" beams.

The electrostatic signal plates SP which are disposed in the rear of the target screens are respectively coupled to the cathodes of the diodes 48a, 48b and 48c by means of capacitors 7a, 7b and 7c. Each said cathode is connected to ground through a resistor 59. A threshold bias is chosen for these diodes such that the noise effects will not be rectified, but only the signal potentials which exceed the value of the steady threshold bias. This bias is obtained by the use of potentiometers 8 connected between the +B supply terminal and ground. The adjustable tap on each of these potentiometers is connected through a resistor 9 to the anode in a respective one of the diodes 48a, 48b and 48c.

The amplitude of the signal potentials resulting from the scanning action of the "take-off" beam greatly exceeds what it would be if the scanning velocity were to be the same as that of the "put-on" beam. Allowing for losses, the ratio of the "take-off" amplitude to the "put-on" amplitude approaches 3 to 1. Hence it is quite practical to clear the diode output circuits of adverse effects from the uninterrupted action of the "put-on" beam in each of the cathode ray tubes 10a, 10b and 10c.

The output from each of the diodes 48a, 48b and 48c is coupled through capacitors 29 to the first grid 28 in an amplifier tube 27, this tube being preferably a pentode. Tube 27 amplifies the signal potentials which are successively derived from the three diodes 48a, 48b and 48c. A similar pentode tube 34 amplifies the synchronizing signal as previously described. The output circuits of the two pentodes are joined together. They have a common load resistor 61 and a common coupling capacitor 47 through which the signals are impressed upon a modulator (not shown) in the radio transmitter.

The input circuit for tube 27 includes components 35, 26 and R8, the same as for tube 34, although their values need not necessarily be the same. The control grid 28 is driven negative by the rectified signals from the three diodes. With due regard for phase reversals additional stages of amplification may optionally be provided.

The circuit arrangement for devices 12, 15, 18 and 20 (Fig. 1) is shown in detail in Fig. 2. From the generator 1 potentials are fed across capacitor 50 and load resistor 51 to ground. They are also fed through resistor 52 to the control grid in a pentode tube 12, which is used as a limiter device. The circuit arrangement for tube 12 is conventional, comprising, as it does, an output circuit resistor 54, a screen grid resistor 55, a cathode resistor 56 and bypass capacitors 57 and 58. Capacitor 57 is connected between the screen grid and ground, while capacitor 58 is in shunt with resistor 56.

The limiter tube 12 produces a substantially square wave output. This output is coupled across capacitor 59 which with resistor 60 acts as a differentiator circuit producing discrete pulses which are fed across capacitor 61 and which are suitable for controlling a saw tooth generator comprising discharge tube 15. Grid current flowing in resistor 62 develops bias for

tube 15 which is stored between pulses in condenser 61. The technique preferably adopted in the differentiator and saw-tooth wave generator is conventional and is well known in the television art. The desired wave shape is, however, insured by the use of a capacitor 65 of proper value coupled across the cathode and anode of tube 15. The value chosen for resistor 69 is also important.

10 A diode rectifier tube 18 is used to clip the peaks off the saw-tooth wave. The cathode in tube 18 is connected to a suitable tap 67 on a voltage divider 68, the latter being connected between the ground and a source of positive D. C. potential indicated by a +B terminal. Resistor 69 is in the anode circuit of tubes 15 and 18.

15 The action of tube 18 is to dissipate all of the energy peaks above and established potential gradient. The energy impressed across capacitor 70 and load resistor 71 is, therefore, of limited duration and is such as to impress the clipped saw-tooth wave potentials on the amplifier tube 20 for only one-third of the total time.

20 Tube 20 is preferably of the beam power amplifier type. Its construction is well known in the art and need not be described herein. This tube, however, is provided with a cathode resistor 73 shunted by capacitor 74. The screen grid resistor 75 has a suitable value for producing the necessary screen grid potential. The screen grid bypass capacitor 76 dissipates alternating potentials on this electrode by diverting them to ground. The output circuit for tube 20 includes the deflecting coils 30 in shunt with a choke 77. 25 A bypass condenser 49 completes the A. C. path to ground.

25 In the operation of the circuit arrangement of Fig. 2 a suitably clipped saw-tooth wave is fed to the deflecting coils 30 and the resultant scanning operation of the "take-off" beam is produced. In this scanning operation, however, it is necessary to provide a centering adjustment and this is obtained by suitable setting of a tap 78 along a potentiometer 79, the latter being connected between the +B terminal and ground.

30 Referring now to Fig. 3 a circuit arrangement is shown which indicates the details of devices 14, 23, and 26 as shown in Fig. 1. The circuit components for the limiter and pulse generator tube 14 are exactly similar to those pertaining to tube 12 in Fig. 2. The function of tube 14 is also the same, that is, it provides a limiting action with respect to the sine wave output from the generator 1. The resistive elements 80 and 82, together with the capacitative elements 81 and 83, constitute a differentiator which alters the shape of the rectangular wave output from tube 14 for suitable control of the grid 84 in a discharge tube 23. This tube delivers a saw-tooth wave across the load resistor 85. The values of resistor 85 and of the associated capacitor 72 are suitably chosen for producing the desired slope of the saw-tooth wave. Utilization of the output is obtained by coupling across capacitor 86 to a grid resistor 87 in the input circuit of amplifier tube 26. The saw-tooth wave is here amplified in the usual manner, and since the circuit arrangements for this tube are conventional they need not be described in detail. The saw-tooth wave potentials are produced across the load resistor 88 and provide beam deflecting potentials across the deflecting plates 22 by coupling the same through capacitor 89. The pair of deflecting plates 22 will be understood to

control the "put-on" beam in any one of the three tubes 10a, 10b, and 10c.

The receiver

It might be well to state briefly the functions which are to be performed by the receiving apparatus in order to separate the received signal into its channel components. As shown in Figs. 4, 5, and 5a, the signal, after suitable amplification by conventional radio receiving apparatus, is directed into different channels, one for the synchronizing component and the other for the intelligence portion of the signal. Figs. 5 and 5a show details of the circuit arrangement. Considering the signal component which constitutes the intelligence for channel A, this is applied to the "put-on" beam of the cathode ray tube 10. However, only one-third of the total time represents the signal applicable to channel A and for the remainder of the distributor cycle a cut-off bias is required so that inappropriate portions of the intelligence signal shall have no effect.

The deflection plates of the tube for channel A, for example, cause the "put-on" beam to have an accelerated scanning velocity such as to completely scan the target from side to side during one-third of the distributor cycle. There are a sufficient number of elemental conductive strips 24 so that the characteristics of the signal remain unaltered but can be reduced to their original frequency by the slower scanning velocity of the "take-off" beam. It will thus be seen that the accelerated modulation frequencies of transmission which are necessitated in order to apply three different trains of signals to the multiplex channel are finally restored in the receiving apparatus to the normal frequencies of the original modulation sources. Each channel considered by itself then delivers a continuous flow of modulations to its responsive device.

Referring now to Fig. 4, conductor 90 is connected to the output side of any suitable receiver. Conductor 90a leads to apparatus which is receptive of the intelligence portion of the signal while conductor 90b feeds to a detector for the synchronizing pulses of the signals. This detector is labelled 91. Its output is fed to an inverter and saw-tooth channel 92 and thence to a device 93 for clipping the peaks of the saw-tooth waves so as to render only one-third of the wave cycle effective for beam deflection in the tube of channel A. The output from the clipper device 93 is, therefore, fed to an amplifier 94 and the output of the latter is utilized for beam deflection as disclosed in more detail in Fig. 5.

A component of output energy from the clipper 93 is also directed into a blanking device 95 which is used for producing a cut-off condition in the "put-on" gun of channel A during two-thirds of each scanning cycle. The technique for accomplishing this will be explained hereinafter.

A 60° delay in the cyclic operation of the deflecting coils associated with the "take-off" beam is produced by the multivibrator circuit 96. This circuit derives its control from the detector unit 91. The output from the multivibrator 96 is fed to a phase inverter and saw-tooth generator 97 and thence to an amplifier 98 for producing suitable beam deflecting energy to be applied to the deflecting coils 30 associated with the "take-off" beam.

Another energy component derived from the multivibrator 96 is directed into a circuit arrangement for channel B which is in all respects simi-

lar to that which has just now been described pertaining to channel A. Thus, the output from the multivibrator device 99b has a 120° phase lag relative to the output pulses from the detector unit 91. The interconnections between the different units 91, 96, 99b, 96b, 99c and 96c are made such that a 60° phase delay takes place in each step. The channel time is, therefore, divided between channels A, B, and C so as to suitably distribute intelligence signals into their respective responsive devices.

In view of the similarity between the circuit arrangements appropriate to the different channels, it is not necessary to further describe Fig. 4. Reference will, therefore, be made to Figs. 5 and 5a for the circuit details which may be considered in connection with any one of the multiplex channels.

In the upper portion of Fig. 5 I show four electronic tubes which represent portions of the scanning circuit arrangement for the "put-on" beams. The diode detector 100 has its cathode coupled through capacitor 101 to the conductor 90 from which the signals are derived from the receiver. A threshold action is produced in the diode by virtue of the connection of its anode through resistor 102 and a tap on the potentiometer 103. This potentiometer is connected between the +B terminal of a direct current source and ground. The rectifying circuit of the diode 100 is completed through resistor 104 which is connected between the cathode and ground.

Across capacitor 105 potentials are fed to the grid 106 of an inverter device which comprises the left section of a twin triode tube 107. The grid control results from variations in the potential drop across the input circuit resistor 108 connecting the grid 106 with ground. The phase inverter device has a cathode resistor 109 connecting the cathode with ground and this resistor is shunted by a capacitor 110.

The output from the phase inverter section of tube 107 is fed to grid 111 of the right hand triode section of this tube. The grid control potentials are reflected in variations of potential drop across the input circuit resistor 112, these variations being produced by coupling the anode of the phase inverter device to the grid 111 across capacitor 113. The two anodes in tube 107 are fed with +B potential across resistors 114 and 115 respectively.

A saw-tooth wave is delivered as output energy from the right hand section of tube 107 and is modified by a clipper device consisting of the diode tube 116 and associated circuit connections. The cathode of tube 116 is coupled to ground across capacitor 117 and is conductively connected to ground through a potentiometer 118, the latter being disposed across the terminals of the +B source.

As is well understood by those skilled in the art, tube 116 operates to clip the peaks of the saw-tooth wave by a suitable amount so that the slope of the saw-tooth wave shall extend only through one-third of the scanning cycle. This slope of the wave is utilized for beam deflection, while the horizontal portion of the wave is co-extensive with the blanking operation applied to the cathode 16 in the "put-on" gun of the tube 10.

The deflection potentials represented by the utilizable slope of the saw-tooth wave are coupled across capacitor 119 to the control grid of an amplifier tube 120. This tube is preferably of the pentode type and its circuit connections are con-

ventional. The grid resistor 121 is shown connected between the control grid 122 and ground. The output circuit for tube 120, having conventional components, is coupled across capacitor 123 to one of the deflecting plates 22 in the "put-on" section of tube 10.

It will be understood from the foregoing description that deflection is produced by the opposing electrostatic plates 22 such as to scan the target 11 in one-third of the distributor cycle. During the remaining two-thirds of this cycle the beam is blanked out. A centering adjustment for the beam deflection is obtained by means of a potentiometer 124 and the impedance 125 which is connected between the tap on this potentiometer and the lead to the ungrounded deflecting plate 22. Suitable adjustment of the biasing potential applied to this plate is, therefore, obtained by connecting the terminals of the potentiometer 124 between points of fixed direct current potential, which may, for example, be considered as having the values +50 volts and -50 volts when referred to a zero-volt ground potential.

A circuit comprising the twin triode tube 126 is provided for suitably blanking the "put-on" beam so that an individual tube 10 will function only with respect to the signals of a particular multiplex channel. The control of the left hand section of tube 126 is derived from the output circuit in the right hand section of tube 107. That is to say, a derivative of the saw-tooth wave produced by this right hand section of tube 107 is applied to the control grid on the left side of tube 126.

The two triode sections of tube 126 in combination serve to produce a square wave derivative of the clipped saw-tooth output from the generator 107. The right hand section of tube 126 is controlled by the left hand section and its cut-off condition persists during two-thirds of the cycle corresponding to the truncated portion of the saw-tooth wave. The right hand section of tube 126 is also conductive during one-third of the cycle corresponding to the slope of the saw-tooth wave. During this one-third cycle, a negative pulse is fed across capacitor 127 so as to bias the cathode 16 in the cathode ray tube more negatively. The "put-on" gun, therefore, functions in phase agreement with the beam deflection. The more positive bias which is applied to the cathode 16 during the remainder of the cycle acts to blank out the signal portions which are intended for other "put-on" guns in cathode ray tubes corresponding to the other intelligence channels of the multiplex system.

In the immediately preceding paragraphs the signal effects are shown to be applied to the "put-on" beam in a given tube 10 for a single channel. After suitably delaying the synchronizing impulses so as to produce phase displaced operations in the other cathode ray tubes 10 of the receiver, the same functions are performed for reception of the signal trains appropriate to the other channels. The phase relations between the different groups of apparatus for channel A, channel B, and channel C have already been explained with reference to Fig. 4. It remains, however, to point out the details of phase control as shown in Fig. 5a.

The means for producing a 60° delay in the start of the scanning sweep of the "take-off" beam, relative to the start of the scanning sweep of the "put-on" beam in the same cathode ray tube comprises a multivibrator tube 96. This tube is pref-

erably of the twin triode type. Associated with its input and output electrodes are the usual time constant impedance, together with cross-coupling capacitors, whereby a rectangular wave is produced in response to the synchronizing impulses. The phase relation between the input and output is adjusted to the desired angle, namely, 60°. The potential on the anode 53 rises and falls cyclically and delivers control pulses across capacitor 63 and the input circuit resistor 66 for the left triode section of the twin triode tube 97. This side of the tube functions as a phase inverter. It is resistance-coupled to the right triode section of the same tube, the latter having for its function to generate saw-tooth waves for controlling the scanning action of the "take-off" beam. The saw-tooth wave potentials are coupled across capacitor 70 to the grid of a beam power amplifier tube 98. This tube may be of the same type as tube 20 in the transmitter, and may be provided with corresponding circuit components. Hence, the latter are given like reference numerals and need not be further described. After amplification by the tube 98, the sweep circuit potentials are applied to the deflecting coils 30, as shown in Fig. 5.

The multivibrator device 99b operates under control of output pulses from the similar device 96. The circuit parameters are similarly chosen for producing a further delay amounting to 60° in the output component of the synchronizing pulses. The result is that the output pulses from the multivibrator 99b are delayed by 120° with respect to the synchronizing signals issuing from the radio receiver.

The synchronizing pulse delay functions which are performed in successive stages by the multivibrator units 99b, 96b, 99c, and 96c are such as to maintain proper phase relations between the different beam scanning operations, also between the blanking operations in the cathode ray tubes for channels B and C. The overall channel time is, therefore, suitably divided between the three channels. Separate responsive devices for each channel are served exclusively with the intelligence signals appropriate thereto.

It will be understood, of course, that modifications of my invention may be made in many ways without departing from the spirit of the invention. The number of intelligence channels to be multiplexed need not necessarily be three, but may be any practical number of channels from two up. Only the phase relations between the cyclic operations of the different cathode ray scannings need be changed if a four-channel system were to be substituted for a three-channel system for example.

One of the advantages to be derived from the use of my invention, particularly if it is to be worked for radio telephony, is that the modulations as transmitted are at frequencies so much greater than the normal voice frequencies as to be practically unintelligible to an unauthorized recipient. The scrambling of these multiplied modulation frequencies as derived from the different channel sources adds further to the secrecy characteristics of the system. I am acquainted with secrecy systems of the prior art which use multiplied or divided modulation frequencies, but, so far as I am aware, I am the first to disclose a multiplex distributor which inherently operates as a modulation frequency multiplier at the transmitting station, and as a modulation frequency divider at the receiving station.

It will be appreciated by those skilled in the art that in practicing my invention I am not

limited to the use of cathode ray tubes having the precise constructional arrangements shown in the aforementioned application of Iams et al. Other cathode ray tubes are known which employ two electronic guns. Some of these are designed to project electron beams from opposite sides of the screen. For example, Iams Patent No. 2,269,588, issued January 13, 1942, shows a cathode ray tube of that type. It is apparent, therefore, that one of the guns in such tube might be used as the "put-on" gun, while the other gun is used as a "take-off" gun.

It is also well within the scope of my invention to use a cathode ray tube similar to an Iconoscope which would have a standard mosaic and which would employ a second gun directed at the same face of the mosaic. In this case the "put-on" and "take-off" beams are caused to strike successively the same spot. The differentiation between the "put-on" and "take-off" beam action is obtained by the use of high velocity and low velocity beams respectively. As previously explained, the high velocity "put-on" beam produces secondary emission which accumulates variable positive charges on the screen. These charges are removed by the low velocity "take-off" beam.

Still another modification of my invention may be practiced by those skilled in the art by the adoption of cathode ray tubes having means embodied therein for rotary scanning of the beams. Thus it is well known that by maintaining two beam deflection potentials in a 90° phase relation one to the other, scanning in a circular path may be obtained. The screen in this case may also be of the standard mosaic construction used in Iconoscopes, if desired.

Various other modifications of my invention may also be made without departing from the spirit thereof.

I claim:

1. A multiplex communication system comprising a plurality of electron discharge tubes each appropriate to a different multiplex channel, a common transmission medium coupled to said tubes, each said tube containing a single storage screen having a multiplicity of parallel conductors, each tube also containing two cathode ray guns each arranged to project an electron beam toward said screen for scanning said conductors in a ratio greater than unity, one of said guns emitting a high velocity beam which stores the signal on said storage screen, the other of said guns emitting a low velocity beam which "takes-off" the stored signal, a beam deflecting device associated with each gun, a saw-tooth wave generator for actuating each one of said deflecting devices, means for synchronizing the scanning strokes of said beam deflecting devices while maintaining phase displacements therebetween, and means including delay circuits coupled to said common transmission medium for causing the scanning stroke produced by one deflecting device in each tube to be completed in a fractional part of the continuous scanning cycle effective for the other said deflecting device in each tube.

2. A multiplex communication system comprising an electronic storage device individual to each channel, each said device including a scanable screen-like array of linear conductive elements of a single electrostatic target, means in said device for emitting a signal-modulated electron beam and projecting said beam toward said target at such high velocity as to cause secondary

emission from said target at the focal point of said beam, means for cyclically deflecting said beam transversely across said linear conductive elements, means for collecting the secondary electrons released by said beam, thereby to effect the storage of positive charges on different ones of said linear conductive elements of the target corresponding to the modulation characteristics of a portion of a signal train, a low velocity electron beam emitting means for successively removing the stored positive charges from different parts of said target, and means operable in synchronism with the cyclic scanning rate of said storage device for deflecting the low velocity beam in such manner as to alter the modulation frequency range of the stored signals and to deliver the same to a utilization device.

3. In a multiplex distributor which terminates signal channels in a multiplex communication system, a plurality of cathode ray tube devices each individual to a respective multiplex signal channel, each said device comprising an electronic "put-on" gun and an electronic "take-off" gun, said guns being adapted and arranged to emit high velocity and low velocity electron beams respectively, beam deflecting means individually associated each with a gun, a single target screen in each said device arranged to be scanned by both of its beams, said target being composed of a multiplicity of elemental electrostatic plates insulated one from another, a single plate separated from said elemental plates by a dielectric, an amplifier under control of potential charges removed from all of the single plates of the several cathode ray tube devices in accordance with the scanning action of said low velocity beams, and means for effecting sequential scanning operations in respect to the different low velocity beams whereby the signals simultaneously and continuously stored by the different high velocity beams are successively taken off for each signal channel at mutually exclusive time intervals, the modulation frequencies of said signals being multiplied for the purpose of substantially distortionless multiplex transmission.

4. In a multiplex distributor which terminates signal channels in a multiplex communication system, a plurality of cathode ray tube devices each individual to a respective multiplex signal channel, each said device comprising an electronic "put-on" gun and an electronic "take-off" gun, said guns being adapted and arranged to emit high velocity and low velocity electron beams respectively, beam deflecting means individually associated each with a gun, a target in each said device arranged to be scanned by both of its beams, said target being composed of a multiplicity of elemental electrostatic plates insulated one from another, a single plate separated from said elemental plates by a dielectric, a plurality of amplifiers each individually controlled by a respective one of said single plates in accordance with the scanning action of the "take-off" gun in a corresponding cathode ray tube device, means for blanking out the control of each "put-on" gun during the reception of signals other than those appropriately assignable thereto, means for maintaining synchronism between the several scanning actions effective upon the different beams, means including delay circuits coupled to the common circuit of said multiplex system for sequentially operating the different "put-on" beams in each scanning cycle, and means including delay circuits also coupled

to said common circuit for operating the "take-off" scanning operations for the different channels sequentially and substantially continuously.

5. In a multiplex communication system having signal storage means of the type wherein capacitive charges are stored on and taken off from a multiplicity of target elements in a cathode ray tube and a separate cathode ray tube is provided for each multiplex channel, the method of multiplexing which comprises impressing the modulations of different trains of signals respectively on separate electron beams, causing each beam to scan its target array continuously, producing accelerated scanning excursions of different "take-off" beams, each of which is directed toward an appropriate one of the different target arrays, thereby to remove the stored charges from said target arrays successively and during mutually exclusive time intervals, and transmitting the multiplexed signals which are derived from said accelerated scanning excursions.

6. In a multiplex communication system having signal storage means of the type wherein capacitive charges are stored on and taken off from a multiplicity of target elements in a cathode ray tube, a separate cathode ray tube being provided for each multiplex channel, and each cathode ray tube having two electron guns therein, one for emitting a "put-on" beam and the other for emitting a "take-off" beam, the method of distributing multiplex signals to different channel receivers which comprises modulating the "put-on" beams of the different cathode ray tubes intermittently and in such manner that each beam stores on its target elements only that portion of the signals which is appropriate to a single channel of said multiplex system, blanking the action of each said beam during portions of the scanning cycle which pertain to other channels, producing continuous scanning excursions in each tube so as to "take-off" the stored charges from the different target arrays therein, and feeding the channel-separated signals to said receivers separately in accordance with the respective continuous scanning excursions.

7. In a multiplex communication system, a double-gun cathode ray tube for each channel, each tube having a high velocity "put-on" gun in combination with means for deflecting its beam continuously under control of a saw-tooth wave, and a low velocity "take-off" gun in combination with means for deflecting its beam intermittently and during times allotted to a single channel, a target in each tube arranged to be scanned by the beams emitted from both of said guns, said target being composed of a plurality of parallel-disposed linear conductors insulated one from another and from a common back plate, and occupying a cylindrical surface whose generating axis intersects at right angles the axes of said guns, said back plate being separated from said linear conductors by a dielectric of substantially uniform thickness, a phase shifting network operable to delay the "take-off" scanning operation with respect to the "put-on" scanning operation in each tube, thereby to provide for complete capacitive storage on said target and complete release therefrom of each portion of the signal train which is comprehended within a scanning cycle of the "put-on" beam, means for accelerating the "take-off" scanning operation with respect to the "put-on" scanning operation, and means for maintaining fixed phase displacements between the "take-off" scanning operations in the different tubes

such that a common output circuit for the multiplex system may be fed with signals derived from the different "take-off" scanning operations successively and at mutually exclusive times.

8. In a multiplex communication system, a double-gun cathode ray tube for each channel, each tube having a high velocity "put-on" gun, a "take-off" gun in each said tube operable at a low velocity of emission, and means including saw-tooth wave generators for deflecting the beams of the different "take-off" guns so that their sweeps are sequential and occupy mutually exclusive portions of the scanning cycle.

9. The combination according to claim 8 and including blanking means operable upon the beams of the different "put-on" guns in such manner that each gun functions to store signals appropriate to a respective one of the multiplex channels.

10. The combination according to claim 8 and including a saw-tooth wave generator and clipper device for separately controlling said deflecting means which are individual to the different "put-on" guns.

11. In a multiplex communication system, a double-gun cathode ray tube for each channel, each tube having a "put-on" gun, a "take-off" gun in each said tube, and means including saw-tooth wave generators for deflecting the beams of the different "take-off" guns so that their sweeps are sequential and occupy mutually exclusive portions of the scanning cycle.

12. A multiplex system for the transmission and reception of a plurality of simultaneously originated telephone signals and the like, said system comprising cathode ray tube signal storage means at points of transmission and reception, means utilizing signal storage means to render the multiple storage of signals continuous at the point of transmission, cathode ray tube scanning means at the point of transmission for frequency-multiplying the signal waves, said scanning means being also effective to compress said waves into distributive time intervals which are individual to the different multiplex channels, a plurality of cathode ray tube signal storage units at the point or points of reception, each said storage unit comprising a cathode ray tube appropriate to each of the multiplex channels, means in each said receiving tube for selecting the discrete portions of the multiplexed incoming signal wave train which are appropriate to a given one of the multiplex channels and for suppressing the effects of other channel portions of said train, and electron beam deflecting means for frequency dividing the selected signal wave portions and for expanding the same so that their original continuity is restored.

13. In a multiplex system, a first vacuum tube comprising an envelope having an electron receiving target and a pair of electron guns, means for causing said guns to scan said target at different speeds and at a predetermined phase relation other than zero, a source of signals for modulating the electron beam emanating from one of said guns, a second similarly constructed vacuum tube having in circuit therewith means for causing the guns thereof to scan its target at different speeds and at a predetermined phase relation other than zero, and another source of signals for modulating the electron beam emanating from one of the guns of the second tube, a generator, and connections from said generator for synchronizing the operation of both said vacuum tubes at a phase relation other than zero.

14. A system in accordance with claim 13, including a common output circuit coupled to the targets on both tubes.

15. An electronic distributor for multiplex communication systems comprising means for utilizing a communications channel in such manner that each signal train in its entirety is divided into discrete channel time units, each unit comprising a frequency-multiplied and compressed portion of said train, means for allocating the channel time units to the different multiplex channels in successive order, multiple means including cathode ray tubes of the double gun type for segregating and storing different portions of the multiplexed signals which are appropriate to each channel, including other cathode ray tubes of the double gun type for expanding said signals after reception and storage thereby to restore their original frequency characteristics and continuity.

16. In a multiplex communication system, a double gun tube for each channel, each tube having a "put-on" gun and a "take-off" gun, means including sweep circuits individual to said tubes for deflecting the beams of the different "take-

10
15

20
25

off" guns and including delay circuits between the different channels for assuring that the sweeps of said sweep circuits are sequential and occupy mutually exclusive portions of the scanning cycle.

17. In a multiplex communication system, a double gun tube for each channel, each tube having a "put-on" gun and a "take-off" gun, means including sweep circuits individual to said "put-on" guns for deflecting the beams of the different "put-on" guns in overlapping time durations, and other sweep circuits individual to said "take-off" guns for deflecting the beams of said "take-off" guns in mutually exclusive time durations.

MAX H. MESNER.
